UNITED STATES PATENT OFFICE.

RICHARD C. TILGHMAN, OF WASHINGTON, DISTRICT OF COLUMBIA.

DESIGN FOR A SIGNPOST.

54,876.

Specification for Design.

Patented Apr. 13, 1920.

Application filed November 18, 1919. Serial No. 338,977. Term of patent 7 years.

To all whom it may concern:

Be it known that I, RICHARD C. TILGHMAN, a citizen of the United States, residing at Washington, in the District of Columbia, have invented a new, original, and ornamental Design for a Signpost, of which the following is a specification, reference being had to the accompanying drawing, forming part thereof.

The figure is a perspective view of a signpost showing my new design.

I claim:

The ornamental design for a signpost, as shown.

In testimony whereof I hereunto affix my signature.

RICHARD C. TILGHMAN.
